UNITED STATES PATENT OFFICE

CHARLES HOWARD JENKINS, OF CHICAGO, ILLINOIS, ASSIGNOR TO JENKINS
PETROLEUM PROCESS COMPANY, A CORPORATION OF WISCONSIN

PROCESSES AND APPARATUS FOR TREATING HEAVIER HYDROCARBONS

Application filed May 10, 1928. Serial No. 276,676.

My present invention relates to improvements in processes and apparatus for treating heavier hydrocarbons, such as petroleum oils, and particularly to a process and apparatus by means of which the yield and quality of light condensable oils produced from such heavier oils are respectively increased and improved above similar products obtainable by the employment of other processes and apparatus.

I accomplish this result through the use of specially prepared oil and certain new and improved apparatus which imparts such high velocity and extreme turbulency to the oil in the still that the condition of such oil throughout its entire circulatory course within the still is, as to temperature, pressure, dispersion of solids and rate of gasoline formation so nearly identical that variation as to these characteristics in different parts of the still is reduced to the zero or vanishing point. Thus the deposition of carbon and other solids is prevented, and necessity of closing down a still for the purpose of removing deposits of accumulated solids is entirely obviated.

The term "zero or vanishing point" as used in this application is to be understood as meaning that conditions are so nearly identical that variation, if any, is inconsequential and virtually negligible.

I have found that in order to accomplish the best possible results in the pressure treatment of petroleum oil for the production of gasoline in an apparatus of the type shown and described in United States Patent #1,321,749, dated November 11, 1919, it is essential that the oil under treatment be driven around its circulatory course within the still at such high speed that only a very small increment of heat is imparted to the oil during its passage through the heating zone and that the time required for the oil to pass through the remainder of its circulatory course back to the entrance of the heating zone be so short that the loss of heat during its course from the exit to the entrance to said zone shall cause no appreciable drop in temperature. When such condition as to extreme rapidity of circulation is attained it

is accompanied by the desired turbulency of the oil throughout its entire circulatory course within the still, by a condition of uniform dispersion of solids and by a rate of gasoline formation which are constant throughout all parts of the body of oil in the container.

While by means of the apparatus and process shown and described in United States Patent #1,321,749, above mentioned, it is possible to maintain throughout the circulatory course within the still a condition of the oil as to temperature, pressure, and dispersion of solids more nearly uniform than in any other apparatus within my knowledge, I have found that by the utilization of the improved apparatus and process of my present invention, it is possible to obtain a uniformity as to the condition of the oil in all parts of the container with reference to temperature, pressure, dispersion of solids and rate of gasoline formation which insures beneficial results as to quantity and quality of product which are otherwise impossible of attainment.

In the practice of the process to which the invention relates, light oils are obtained from specially prepared heavier hydrocarbons by treatment of the latter in a closed still comprising an upper longitudinal drum superimposed over a bank of tubes expanded into front and rear transverse drums, the latter being connected to the upper drum by suitable sluiceways, in one of which sluiceways a positive circulatory device is installed. The process involves continuous treatment of cracking stock, consisting of liquid hydrocarbons having a finely divided adsorptive dispersed therein, at a cracking temperature by external application of heat to tubes; continuously introducing additional cracking stock with coincident withdrawal of vapors and degraded stock; and simultaneously with the above operations, continuously subjecting the liquid content of still to a constant and very high rate of circulation.

This positive circulating device produces such rapid circulation in the still that in controlling the extent of cracking by regulating the amount of hydrocarbons flowing to and

from the still the rapid velocity of the circulating oil within the still is not appreciably affected. The circulation of the oil while undergoing cracking is entirely independent 5 of the amount of oil supplied to or withdrawn from the still.

It is an object of this invention to increase the speed and positiveness of circulation so that the entire body of cracking stock in the 10 still will be driven quickly and repeatedly through the heating zone and there have imparted to it in rapid succession small increments of heat whereby such entire body of cracking stock may be maintained in a condition of uniformity as to temperature, pressure, dispersion of solids and rate of gasoline 15 formation; a highly important secondary result of such uniformity in heat application being the greater production of lighter hydrocarbons of superior anti-knock character than was formerly obtained.

Another object of the invention is to develop a perfectly mechanically balanced rotative action to the positive circulatory device, thus securing a minimum of vibration 25 with its attendant evils of wear and tear to bearings, frequency of shut-down for repairs, high maintenance costs, and indirect overhead charges for idle periods.

Still another feature of the invention is to introduce a positive scouring rotative centrifugal force on the walls of the vertical sluiceway containing the improved propeller, before such force is translated from its vortex effect into a positive drive through the 30 tubes.

Contra vortexes and scouring effects may be induced by a reversal of the circulation, if desired, but I employ preferably a positive 40 propeller of a size and operated at a speed sufficient to obtain my objectives.

To a limited extent, increased speed and positiveness of circulation required by new demands in thermal efficiency, quality of 45 product, and problems that have arisen incident to the introduction of solid adsorptives to the still, have been met by increasing the speed of the simple type of propeller described in United States Patent No. 1,226, 50 526, but such has been accomplished only at the expense of a disproportionate consumption of power, and often induces excessive vibration.

Another suggested method to obtain the 55 desired increase in rate and positiveness of circulation is the employment of a large size propeller operating at normal speed, but such method is limited in that the requisite diameter of sluiceway to house such a propeller 60 would necessitate excessively heavy reinforcing of sluiceway openings.

In brief, circumscribed by the above practical operating limits, former practice develops an average circulatory speed of about 65 ten feet to twelve feet per second through

the tubes, which rate has proven insufficient to prevent a film of carbon depositing on the inner walls thereof, thus decreasing the rate of heat transfer and ultimately shortening the run. The speeds heretofore attained 70 have also failed to maintain a constant and uniform dispersion of suspended solids throughout the entire liquid body within the still and have also fallen short of the attainment of optimum results from the use of 75 adsorptive substances in cases where such adsorptives must be used in relatively large amounts.

By introducing my improved positive balanced type of propeller, I eliminate vibration at high propeller speeds and also minimize backlash, thus insuring full realization 80 of the benefits to be derived from my improved process and apparatus.

The design of my improved positive propeller admits, within certain well known laws of mechanics, a reduction both in speed of rotation and in diameter, coincident with an increased rapidity of circulation as compared with a propeller of the ordinary rimless type; and while not limiting myself to any figure, I find it possible under the above 90 conditions to obtain and I now preferably employ a rate of upwards of eighteen feet per second through the tube bank. The reduced diameter of propeller moreover permits a corresponding decrease in size of sluiceway, thus effecting an increased factor of safety both in the propeller proper and in its container, highly important items 100 in pressure still construction.

While present development tends toward greater speed of circulation, I find the rate of eighteen feet to twenty feet per second now sufficient to prevent deposition of any solid material, thus maintaining a constant and uniform dispersion of active as well as inert components throughout the entire liquid body of the still. The maintenance of a uniform dispersion of all active constituents leads to a regular breaking down of the molecular structure of the heavier hydrocarbons, and this in conjunction with the benefits derived from increased speed of circulation and consequent shorter periods of time during which the molecules are subjected to the heat influx, results in the lighter desirable hydrocarbons produced retaining unchanged the maximum number of the branch chains of the heavier molecules of the original charge, thus producing a gasoline high in anti-knock value.

The advantage of a speed sufficient to maintain a constant percentage suspension of solid bodies has been mentioned, this being highly important in the case of adsorptives requiring an appreciable interval of time to develop their maximum effect, or where such substances are to be used in high concentration. For instance, with certain stocks high 125 130

in asphaltine content it frequently becomes necessary to use from one to five pounds of a typical adsorptive such as hydrated lime per barrel of charging stock in order to achieve optimum results. The dispersion of this large amount of lime requires a high rate of circulation such as that made possible by my improved apparatus.

With the cleanliness of tubes produced by 10 the increased positiveness and force of circulation, there occurs a maximum rate of heat interchange, with a corresponding reduction in fuel consumption; while coincident with the above conditions, due to the increased 15 speed of circulation, a minimum increment of heat is transferred per pound of oil passing through the heating zone, the molecules of the bulk charge being thus progressively and uniformly heated under an increased 20 number of rapidly recurrent cycles. Such regular and mild cracking conditions result not only in the minimum degradation of the recycle stock recovered from the bulk charge reject, but also in the lowest attainable yield 25 of permanent gases.

I have obtained the desired increase in speed and positiveness of circulation with the above described correlative and coincident improvements to my process by using 30 a new form of positive propeller, comprising a perfectly balanced fly-wheel rim of substantial weight, sufficient to secure an inertia of exceedingly regular rotation against possible surges under changes of hydraulic head; the 35 fly-wheel rim being united to the hub through a plurality of blades, of which I employ four by preference, the latter being set at a pitch best suited to obtain the increased circulation and positiveness of effect desired.

40 The improved positive propeller may be fabricated in a single casting, but as a relatively larger man-neck is necessary to introduce or withdraw same, when so manufactured, from its operative position within the 45 still, I prefer to have the propeller made in two or more sections and assembled within the still, thus being able to materially decrease the size of the man-neck required to admit the propeller, with a corresponding in- 50 crease in factor of safety in still construction.

I preferably develop the propeller from a solid casting, split along a diameter bisecting the angle between two blades in sequence, locking the sections of the hub with a top 55 right-handed and bottom left-handed tapped lock-nut respectively, and uniting the rim by riveted or welded joints of sufficient strength as to properly withstand the stresses set up therein when rotated.

60 The reverse threaded lock-nuts are employed so that the usual rotation of the propeller will serve to tighten the nuts in question; the top nut being of hemispherical or conical form, the better to deflect the circula- 65 tory stream to the blades of the propeller,

while the bottom nut is of paraboloid shape to diminish resistance although I do not necessarily limit myself to these forms.

My improved propeller is preferably mounted in the rear vertical sluiceway on a 70 shaft extending downwardly through the upper longitudinal drum of the still into such sluiceway, said shaft being driven by a motor mounted on the still. Immediately 75 above the rim of the propeller and attached to the inner wall of the sluiceway is an annular orifice plate, which plate together with the propeller, its bearings, the means for locking it on the shaft, and the adjacent walls of the sluiceway may be termed the propeller 80 assembly. The upper side of the orifice plate is tapered and the upper face of the rim of the propeller is located close below said plate, this arrangement having the effect of minimizing backlash and facilitating the 85 flow of the oil into the propeller.

In the accompanying drawings Figure 1 is a sectional side elevation of a type of apparatus suitable for the use of my improved process. Figure 2 represents a detailed plan 90 of the propeller detached from the shaft, Figure 3 is an enlarged sectional elevation of the positive propeller mounted in rear sluiceway. And Figure 4 is a fractional view of a modified form of my improved propeller and 95 the adjacent portion of the still.

The heavier oil to be processed is continuously forced through feed pipe 1, in which there is a check-valve 2, and control valve 3, by pump 4, to distributing L 5 in top of 100 baffle tower 6 having the baffle plates 6'; the oil meeting in its downward path in counter-current manner the ascending hot cracked gasoline vapors entering the base of baffle tower through the line 7, from the still 8; 103 the lighter partially dephlegmated gasoline produced passing out from the top of the tower through line 9, past control pressure valve 10, to be further refined; the baffle tower reject returning to still through run- 110 back line 11.

The still 8, consisting of an upper longitudinal drum 12, superimposed over a bank of tubes 13, expanded into front and rear transverse drums 14 and 15 respectively, which 115 are in turn connected to upper drum by front and rear sluiceways 16 and 17 is heated by a furnace 18 to a temperature and at a pressure best suited to obtain the desired objectives in yield and composition of product 120 desired, excessive pressure being relieved by safety valve 19.

The still, the several parts of which are set 125 forth above, constitute the cracking zone in which conditions of temperature and dispersion of solids are maintained so uniform throughout by means of the propeller with its balanced fly-wheel rim and superimposed orifice plate, that any variation in conditions

of temperature or dispersion of solids approaches the zero or vanishing point.

Oil is maintained in the still at level 20 indicated by gauge 21, continuously discharging from the still, past control valve 22, through draw-off line 23, at a rate (influenced by quality of gasoline produced, baffle tower reject, and speed of feed) that is essentially a constantly substantial percentage of the bulk still contents; such discharge being later vaporized at low pressure in other apparatus to give up its more valuable constituents before ultimate rejection as heavy residuum.

16. Coincident with the above described continuous operations, the entire bulk charge of the still is maintained in constant circulation by the propeller 24, mounted on shaft 25, extending through stuffing box 26 and driven 20 by motor 27.

Figure 2 represents the development of the propeller from the two half sections 28 and 28'; the split hub 29, blades 30, rim 31, and riveted joints 32 and 32' being clearly shown.

23. In Figure 3, the propeller is shown mounted on shaft 25, reduced to taper fit 33, and locked by key 34. On the upper and lower bosses of the hub 29, are screwed the top and bottom reverse tapped lock-nuts 35 and 36. The blades 30 appear in the drawing partly in elevation and partly in cross section, the fly-wheel in full cross section. A deflecting cone or orifice plate 37, located immediately above and projecting over fly-wheel rim 31, serves to reduce fluid friction and minimize backlash.

26. In Figure 4 is shown a fractional cross section of a form of my propeller in which the edges of the rim are beveled, thus obviating the necessity for the orifice plate; I prefer, however, to employ the plate and the form of propeller rim shown in Figure 3.

The shaft is held in rotative alignment in the sluiceway 17 by the bearing 38, the 45 thrust of rotation being taken care of by the upper thrust bearing 39 shown in Figure 1.

The still has man-necks 40 through which the positive propeller, preferably in two sections, enters the still.

50. This invention is not restricted to the precise speeds, rates and times set forth, nor to the apparatus shown and described.

That portion of the still which comprises the upper longitudinal drum, the underlying 55 sluiceways, the transverse drums and the heating tubes is adapted to contain the main body of oil in the still, and it is therefore herein referred to as a container. Moreover, since the entire body of oil in the container 60 is driven by the propeller through the longitudinal drum, the sluiceways, the transverse drums and the heating tubes in a cyclic manner, it is apparent that the container forms what may be termed an enclosed cyclic 66 channel.

What I claim is:

1. The process of continuously producing gasoline and other light oils from charging stock comprising heavier hydrocarbons, which consists in continuously heating such 70 charging stock at a cracking temperature in a closed still; supplying during the run additional charging stock to the still; continuously taking off vapors; rejecting during the run part of the still contents; and forcing the entire liquid contents of the still therethrough under the action of circulating means adapted to create and translate whirling vortex effects into a positive driving force whereby such high velocity is obtained that the conditions throughout such still contents are, as to temperature and composition, so 75 nearly identical that variation as to these characteristics in different parts of the still approaches the zero or vanishing point. 80

2. The process of continuously producing gasoline and other light oils from charging stock comprising heavier hydrocarbons, which consists in continuously heating such 90 charging stock at a cracking temperature in a closed still; continuously supplying additional charging stock to the still; continuously taking off vapors; withdrawing during the run a portion of the still contents; and mechanically effecting such a turbulent 95 and rapid circulation of the entire liquid contents of the still that the conditions of temperature and composition are so nearly identical throughout said still that variation as to these characteristics approaches the 100 zero or vanishing point.

3. The process of cracking heavier hydrocarbons into lighter hydrocarbons which includes continuously flowing a stream of said heavier hydrocarbons to and from a cracking zone under pressure; extraneously heating a portion of said cracking zone; continuously releasing vaporized hydrocarbons therefrom; and maintaining such a positive and rapid circulation of the hydrocarbons 105 throughout the entire cracking zone independently of the stream of hydrocarbons flowing to and from said cracking zone that variation in conditions of temperature and dispersion of solids throughout the entire cracking zone approaches the zero or vanishing point. 110

4. In an oil cracking still having a circulating passage for the oil undergoing cracking, a propeller having blades operating in said passage, a tapered means in said passage immediately above the propeller for directing oil toward the center of said blades and a rim surrounding said blades and in close proximity to the walls of said passage for preventing slippage of oil from said propeller blades back along the walls of said 115 passage. 120

5. In an oil cracking still comprising a drum, a series of heating tubes and connect- 125

ing passages between said tubes and drum, a restriction in one of said connecting passages, a propeller having blades operating in this passage between said restriction and said tubes, and a rim surrounding said blades and in close proximity to the walls of said passage, said restriction facilitating the flow of oil into said blades and said rim preventing slippage of oil from the ends of said blades back along the walls of said passage.

6. In an oil cracking still having a circulating passage for the oil undergoing cracking, a propeller having blades operating in said passage, a rim surrounding said blades for preventing slippage of oil from said blades back along the walls of said passage, and a deflecting cone overlying said rim for facilitating the flow of oil into said blades.

7. In an oil cracking still comprising a drum, a series of heating tubes and connecting passages between said tubes and drum, a rotative propeller in one of said connecting passages for forcing oil in a given direction through said passage, a fixed orifice plate forming a restriction in said passage immediately preceding said rotative propeller for directing oil thereinto and a rotatable annular member integral with said propeller and directly beneath said orifice plate forming a continuation of the restriction of the orifice plate through the propeller whereby the flow of oil in said passage is increased immediately prior to and throughout the action of the propeller upon the oil.

8. The process of continuously producing gasoline and other light oils from charging stock comprising heavier hydrocarbons admixed with an adsorptive material such as lime hydrate, which consists in continuously heating such charging stock at a cracking temperature in a closed still; continuously supplying additional charging stock containing said adsorptive material to the still; continuously taking off vapors; withdrawing during the run a portion of the still contents including adsorptive material and associated carbon; and mechanically effecting such a turbulent and rapid circulation of the entire liquid contents of the still, including said adsorptive material, that the conditions of temperature and composition are so nearly identical throughout said still that variation as to these characteristics approaches the zero or vanishing point.

9. The process of continuously producing gasoline and other light oils from charging stock comprising heavier hydrocarbons which consists in continuously heating such charging stock at a cracking temperature in a closed still including a bank of heating tubes and a non-extraneously heated drum; continuously supplying additional charging stock to the still; continuously taking off vapors; withdrawing during the run a portion of the still contents; and mechanically effecting such a

turbulent and rapid circulation of the entire liquid contents of the still through said bank of heating tubes and non-extraneously heated drum that conditions of temperature and composition of the oil are maintained so nearly identical at all points in said still that differences in the rate of cracking of the oil in said drum and bank of heating tubes become negligibly small and approach zero.

10. In an oil cracking still comprising a drum, a series of heating tubes and vertical connecting passages between said tubes and drum, a stuffing box opening into said drum over one of said vertical connecting passages, a vertical shaft extending through said stuffing box and drum into said connecting passage, a thrust bearing for supporting said shaft, means attached to said shaft outside the still for causing rapid rotation thereof, propeller blades attached to said shaft within said connecting passage for forcing oil downwardly through said passage and effecting a rapid circulation of the oil through said tubes and drum, and a rim of substantial weight integral with and surrounding said propeller blades for minimizing upward thrust on said bearing when said shaft is rotated and oil is forced downwardly by said propeller blades through said passage and rapidly circulated through said tubes and drum.

11. In an oil cracking still comprising a drum, a series of heating tubes and vertical connecting passages between said tubes and drum, a stuffing box opening into said drum over one of said vertical connecting passages, a vertical shaft extending through said stuffing box and drum into said connecting passage, a thrust bearing for supporting said shaft, means attached to said shaft outside the still for causing rapid rotation thereof, propeller blades attached to said shaft within said connecting passage for forcing oil downwardly through said passage and effecting a rapid circulation of the oil through said tubes and drum, and a beveled rim of substantial weight integral with and surrounding said propeller blades, the outer surface of said rim being disposed in close proximity to the walls of said passage whereby slippage of oil from said propeller blades back along the walls of said passage is reduced and upward thrust on said bearing is minimized when said shaft is rotated and oil is forced downwardly by said propeller blades through said passage and rapidly circulated through said tubes and drum.

In testimony whereof I have affixed my signature.

CHARLES HOWARD JENKINS.

DISCLAIMER

1,827,018. — *Charles Howard Jenkins*, Chicago, Ill. PROCESSES AND APPARATUS FOR TREATING HEAVIER HYDROCARBONS. Patent dated October 13, 1931. Disclaimer filed October 17, 1934, by the assignee, *Jenkins Petroleum Process Company*, and the patentee.

Hereby enter this disclaimer from the scope of claims one (1), two (2), three (3), eight (8) and nine (9) of the aforesaid Letters Patent of any and all processes for cracking hydrocarbon oils, saving and excepting such processes in which the oil undergoing cracking is circulated in a plurality of restricted streams through a bank of heating tubes at a velocity of upwards of eighteen feet per second, thence in an unrestricted stream through a non-extraneously heated drum, and oil from said drum is returned to said bank of heating tubes for re-circulation therethrough, as aforesaid.

And your petitioner hereby enters this disclaimer from the scope of claims four (4), five (5) and six (6) of the aforesaid Letters Patent of any and all constructions, saving and excepting such constructions in which the rim is attached to and rotates with the propeller blades.

[Official Gazette November 13, 1934.]
